(57) **CLAIM**

The ornamental design for an electrical connector, as shown and described.

DESCRIPTION

FIG. 1 is a front elevational view of an electrical connector; FIG. 2 is a top plan view thereof; FIG. 3 is a bottom plan view thereof; FIG. 4 is a rear elevational view thereof; FIG. 5 is a left side elevational view thereof; FIG. 6 is a right side elevational view thereof; and, FIG. 7 is a perspective view of the front and right side thereof. The broken lines in FIG. 4 are included for the purpose of illustrating a portion of the connector that forms no part of the claimed design.
